UNITED STATES PATENT OFFICE.

DENSAKU ARUGA, OF SAN FRANCISCO, CALIFORNIA.

WOVEN CLOTH.

1,358,607.

Specification of Letters Patent. Patented Nov. 9, 1920.

Application filed February 24, 1920. Serial No. 360,651.

To all whom it may concern:

Be it known that I, DENSAKU ARUGA, a subject of the Emperor of Japan, residing at San Francisco, in the county of San Francisco and State of California, have invented new and useful Improvements in Woven Cloth, of which the following is a specification.

This invention relates to an improved weave for cloth and resides in the provision of a cloth owing to which weave is especially adapted for use in shoe insoles.

The primary object of this invention is to provide a cloth which will be comparatively soft and smooth on one side although closely woven and of thick heavy texture, the weave throughout being the same and of such character that binding or hemming the edges to prevent unraveling is unnecessary, thus in cutting the cloth the freshly cut edges will have no tendency to readily unravel and need not be selvaged by a particular weave different from the weave throughout the entire piece.

Another object is to provide cloth in which the weave includes relatively heavy threads and relatively light threads interwoven so that a neat compact pattern is provided and so that the cloth will be stiff and pervious to air but comparatively soft.

The invention possesses other advantages and features, some of which, with the foregoing will be set forth at length in the following description where I shall outline in full that form of the invention which I have selected for illustration in the drawings accompanying and forming a part of the present specification. In said drawings I have shown one form of the construction of my invention but it is to be understood that I do not limit myself to such form, since the invention as expressed in the claims may be embodied in a plurality of forms.

Figure 1 is a fragmentary plan view of a piece of cloth woven in accordance with my invention in which the threads are closely magnified and broken away, to show the manner of weaving;

Fig. 2 is a view similar to Fig. 1 of the reverse side of the cloth;

Fig. 3 is a longitudinal sectional view taken through the cloth;

Fig. 4 is a top plan view of an insole for shoes made from the cloth of this invention.

Referring to the drawings, the cloth of my invention comprises relatively large or heavy warp threads 1, relatively light or smaller woof threads 2 and a plurality of 60 longitudinal or warp locking threads 3 which latter are smaller and finer than the woof threads 2. The warp threads 1 provide body for the cloth whereas the threads 3 are principally used to lock the woof and 65 warp threads so as to bind them closely together whereby the cloth is closely woven and will not unravel at the edges.

The warp threads 1 extend parallel to one another and at right angles to the woof threads 2. Looking at the weave from the upper side of the cloth the warp threads 1 extend in pairs first over a group, for example, six, of the woof threads and then under a smaller group, for example, two, 75 of the next adjacent woof threads this interweaving arrangement continuing throughout the length of the cloth.

To be more explicit, the pair of threads marked *a* in Fig. 1, being the outermost pair 80 of warp threads, extends over six woof threads and under two next adjacent woof threads and so on throughout the length of the cloth, whereas the pair of warp threads designated *b* in Fig. 1 and which is next adjacent to the pair *a* extends under the middle two woof threads of the six passed over by the pair *a* and then over the six adjacent woof threads which latter six includes as the center ones thereof the two woof threads 90 passed under by said pair *a*. Thus the woof threads extend over the warp threads at staggered points. The locking threads 3 extending parallel with the warp threads 1, pass first over and then under each succeeding woof thread and pass between the threads of each pair of the woof threads which extend over the warp threads. These threads 3 extend upon both sides of each pair of warp threads and lie closely alongside 100 said warp threads. Certain of the woof threads extend entirely across the cloth beneath the warp threads such woof threads being designated 3' and shown particularly in Fig. 2 of the drawing. Thus when six 105 threads are passed over by warp threads, four of said six are not interwoven between the warp threads but extend in pairs across the underside of said warp threads. The portions of the pairs of warp threads over 110 which the woof threads extend are forced outwardly between the pair of woof threads

3' and lie in spaced parallel rows on the reverse side of the cloth.

This makes the reverse side rougher than the other side. Cloth woven as described herein will be soft on one side and comparatively rough and hard upon the reverse side and by means of this particular weave the cloth is comparatively thick and stiff. Owing to these characteristics I have found 10 that the cloth is particularly adapted for shoe insoles, accordingly I have illustrated a shoe insole 5 shown in Fig. 4 of the drawings. In using an insole made of cloth of my invention the smooth soft side is the 15 upper side of the insole. The insole need not be stiffened, hemmed or bound in any way around the edges inasmuch as the cloth will not readily unravel. Because of this, such an insole may be cut to suit the particular foot or shoe and this is an advantage not obtainable with insoles of the type now in 20 general use. Due to the peculiar weave of the cloth an insole made from said cloth will not pucker up into ridges or wrinkle and 25 shrink when wet from perspiration.

I claim:—

1. Woven cloth comprising warp threads

and woof threads, said warp threads being arranged in groups, one group extending over a group of woof threads and then under 30 a smaller group of next adjacent threads and the next adjacent groups of warp threads extending under certain woof threads of the larger group over which the first named pair of warp threads extend, and warp threads 35 extending over every other one of said woof threads on each side of each group of warp threads.

2. Woven cloth comprising warp threads and woof threads, said warp threads being 40 arranged in groups, one group extending over a group of woof threads and then under a smaller group of next adjacent threads and the next adjacent groups of warp threads 45 extending under certain woof threads of the larger group over which the first named pair of warp threads extend, certain of said woof threads extending for their entire length beneath the warp threads and warp threads extending parallel to and alongside of the 50 groups of warp threads over and under successive woof threads.

DENSAKU ARUGA.
